PAINT STRIPER

Robert A. Pfleger, Los Angeles, Calif.

Application April 21, 1936, Serial No. 75,586

3 Claims. (Cl. 91—62.6)

This invention relates to a paint stiper. Such stripers in general are known, and include a stiper wheel knurled on its periphery, and arranged to be loaded with paint by extending into a paint reservoir. As the stiper wheel is rolled on a surface to be painted, it leaves a paint stripe thereon.

The wheel is usually rotatably mounted between ears, attached to a barrel or reservoir for the paint or lacquer or the like. The excess paint on the wheel is wiped off, in stripers of the prior art, at the top surface of the ears, where the wheel reenters it as it is rolled on the work. This causes an accumulation of paint at the top portion of the wheel, and it may drop down and cause a blot.

It is one of the objects of this invention to prevent the undesired accumulation of paint, and especially by providing a wiping action that is not restricted to the top portion of the wheel.

It is another object of this invention to provide a simple and inexpensive device of the character referred to.

It is still another object of this invention to provide a paint stiper that can utilize a collapsible tube reservoir instead of the conventional plunger type.

It is still another object of this invention to provide a stiper wheel that is arranged to deposit a line or stripe having a thicker layer at the center of the stripe.

It is still another object of this invention to provide a stiper having a gravity feed, in which the position of the reservoir can be adjusted to make it possible to use the stiper on a surface that is not necessarily horizontal, and yet utilize the gravity feed principle.

This invention possesses many other advantages, and has other objects which may be made more easily apparent from a consideration of several embodiments of the invention. For this purpose there are shown a few forms in the drawing accompanying and forming part of the present specification. These forms will now be described in detail, illustrating the general principles of the invention; but it is to be understood that this detailed description is not to be taken in a limiting sense, since the scope of this invention is best defined by the appended claims.

Referring to the drawing:

Figure 1 is a side elevation of a paint stiper embodying the invention;

Fig. 2 is a front elevation thereof;

Fig. 3 is an enlarged longitudinal section of the device shown in Fig. 1;

Fig. 4 is a view, partly in longitudinal section, of another form of the invention; and

Fig. 5 is an elevation of the stiper head used in connection with the form of the invention illustrated in Fig. 4.

In Figs. 1, 2 and 3, the stiper wheel 1 is illustrated as being adapted to paint a stripe on a surface 2. As is well understood the periphery of this wheel can be knurled or roughened in order to provide a series of shallow recesses for the paint or lacquer. The paint or lacquer is adapted to be accommodated in a gravity feed reservoir 3. This gravity reservoir is shown as of general tubular configuration, closed as by a cap 4.

The stiper wheel 1 is shown as carried by a head 5. This head 5 has a cylindrical recess 6 (Fig. 3) adapted to telescope over the open end of the reservoir 3. In this way a frictional contact can be provided between the head 5 and portion 7 of the reservoir 3, making it possible to adjust the head 5 angularly with respect to the reservoir. Since the other portion of the reservoir 3 diverges at an angle, it is thus possible to maintain the gravity feed reservoir in proper feeding position, irrespective of the slant or position of the surface 2 upon which the stripe is to be placed. Various positions of this adjustment are illustrated by the dot-and-dash lines in Figs. 1 and 2.

The head 5 rotatably supports the wheel 1. For this purpose the head is provided with an ear 8, having a slot 9. The slot 9 closely encompasses the side of the wheel 1; and the wheel is mounted for rotation on a transverse pin 10 extending across the slot 9 and fixed in the ear 8. The slot 9 communicates with the recess 6 and extends so as to intersect the lower portion of the head 5, and to provide a narrow space 11 between the periphery of the wheel 1 and the lower edge of the slot. This space enables the paint to flow from the reservoir 3 and from the recess 6 to the periphery of the wheel 1, as the wheel is drawn along the surface 2 toward the right.

The wheel 1 loaded with the paint thus rotates in a clockwise direction about its own axis. In the usual form of paint stiper, the paint also covers at least some of the exposed areas of the sides of the wheel 1. This paint is wiped off when the wheel reenters the slot 9 at the top of the upper side of the wheel. This causes an accumulation of the paint at that spot, and there is a likelihood that the accumulated paint will drop onto the work, causing a blot or spot.

In order to obviate this, the arrangement is

such that the paint is wiped off by a wiping action that is not restricted to the top portion of the wheel; instead it is wiped off gradually from the bottom to the top of the wheel 1. This is secured by mounting the wheel 1 on an axis which is eccentric to the circular configuration of the ear 8. In this way, that area of the wheel sides which is exposed, narrows as the top of the slot 9 is approached. This results in a gradual wiping of the excess paint from the sides of the wheel, and in ensuring that at least some of the paint will be wiped off the sides before the top of the ear 8 is reached.

The manner in which this gradual wiping is obtained can be explained by reference to Fig. 3. That portion of the wheel 1 which emerges from the bottom of the slot 9, at the area marked 11, reenters the slot 9 gradually, as the wheel rotates. This gradual reentry is due to the eccentric action; and complete reentry is finally accomplished at the top of the slot at the region marked 12, where the line defining the periphery of the wheel intersects the contour of the ear 8. In other words, the exposed area of the wheel sides narrows as the entrance region 12 of the slot 9 is approached.

In order to ensure against corrosion, clogging or wear, the wheel 1 is preferably hard chromium plated. In this way, the wheel can be kept easily free of foreign matter, and can be more readily cleaned.

To provide a guide for the implement, a bent guide bar 13 can be provided. This guide bar includes a portion 14 (Figs. 2 and 3) which extends transversely through a boss 15 formed on the head 5. A thumb screw 16 can hold the bar 13 in any adjusted position. Its guiding leg 16' can be formed by a forwardly directed extension 16'. By adjusting the lateral spacing between the wheel 1 and the portion 16', the running of a stripe at a definite spaced distance from a reference line can be readily accomplished.

It is sometimes advantageous to provide a wide wheel for depositing a wide stripe. In the form shown in Figs. 4 and 5, such a wide wheel 17 is indicated. This wheel, however, instead of

having a flat periphery, has a concave periphery 18. By the aid of this configuration, more paint is deposited adjacent the center of the stripe than at the edges. This is desirable at times to provide an embossed effect.

In this form also, the striper head 19 is adapted to be used in connection with a collapsible tube reservoir 20. For this purpose, it is provided with a threaded recess 21 adapted to be threaded on to the nipple 22 of the tube 20. The manner of use is obvious. As shown most clearly in Fig. 5, the gradual wiping action is secured by eccentric mounting of the wheel 17 in the head 19.

What is claimed is:

1. In a paint striper, a rotatable striper wheel, 15 a paint reservoir, and an ear providing a slot in which the wheel turns, said slot having sides close to the contiguous sides of the wheel, and having a direct communication with the reservoir, said ear providing an axis for the wheel so located 20 that the area of the wheel sides which are exposed, narrows as that part of the slot is approached where the wheel periphery enters, as the wheel rotates in use.

2. In a paint striper, a rotatable striper wheel, 25 a paint reservoir, and an ear providing a slot in which the wheel turns, said slot having sides close to the contiguous sides of the wheel, and having a direct communication with the reservoir, said ear having a general circular configuration, 30 eccentric to the wheel axis, so that the exposed area of the wheel sides narrows as the entrance to the slot is approached, and as the wheel rotates in use.

3. In a paint striper, a rotatable striper wheel, 35 a paint reservoir, a head attached to the reservoir, said head having a hollow portion in communication with the reservoir, said head having an ear providing a slot in which the wheel turns, said slot intersecting the hollow portion of the head, 40 said ear also having a general circular configuration, eccentric to the wheel axis, and of a size approaching that of the wheel, so that the exposed area of the wheel sides narrows as the wheel rotates in use to enter the slot.

ROBERT A. PFLEGER.
